UNITED STATES PATENT OFFICE.

EDWARD D. ARIAN, OF SAN FRANCISCO, CALIFORNIA, ASSIGNOR, BY DIRECT AND MESNE ASSIGNMENTS, OF ONE-THIRD TO CHARLES P. THOMAS, OF SAN FRANCISCO, CALIFORNIA, AND ONE-THIRD TO FRANK J. RICH, OF SAN FRANCISCO, CALIFORNIA; FRANK J. RICH, ADMINISTRATOR OF SAID CHARLES P. THOMAS, DECEASED.

DESICCATOR.

Application filed September 29, 1919. Serial No. 327,069.

To all whom it may concern:

Be it known that I, EDWARD D. ARIAN, a citizen of the United States, residing at the city and county of San Francisco and State of California, have invented new and useful Improvements in Desiccators, of which the following is a specification.

This invention relates to a desiccator for fruits and vegetables. Heretofore various forms of drying apparatus have been provided for dehydrating fruits and vegetables but due to the excessive moisture normally contained in the articles treated, it has been quite a problem to extract this moisture without stewing or burning the articles.

It is the principal object of the present invention to provide a desiccator which will act to thoroughly expel the moisture from the fruit without cooking it and at the same time bring this action about without the application of excessive drying heat which would tend to burn the fruit.

The present invention contemplates the use of a drying chamber, in which a plurality of superimposed drying trays may be placed and which chamber is provided with suitable means for obtaining heated air and fresh air received in any predetermined proportions and drawn off from the chamber with the moisture laden air as the dehydration process progresses.

The invention is illustrated by way of example in the accompanying drawings, in which—

Fig. 1 is a view in plan, showing the complete apparatus and particularly indicating the manner in which a uniform distribution of fresh air is established throughout the structure.

Fig. 2 is a view in central vertical section through the desiccator, further disclosing details of construction thereof.

In the drawings, 10 indicates a drying compartment, which is shown in Fig. 2 having double walls 11 and 12. These walls are spaced a distance from each other to provide an air circulating passageway 13.

In plan, the walls are arranged to form a substantially rectangular compartment 10 and are carried over the top of the compartment to form a circular dome. The dome portion of the compartment extends upwardly a considerable distance above sets

of trays 14, which are provided to carry the material to be dried. It is possible to support the trays directly within the compartment although in Fig. 2 of the drawing it will be seen that cars 15 are used, having a frame work upon which angle members 16 are carried. These angle members are spaced along uprights to provide shelves for the trays 14. The frame work of the cars is carried upon axles 17 fitted with wheels 18. These wheels run along tracks 19 which extend into the compartment and thus permit the car to be loaded and thereafter moved along the track to charge the desiccator. This will, of course, cut down charging time and will also eliminate the loss of time required to remove the trays of dried material from the compartment. The rails 18 are superimposed upon a truss structure 20 and extend directly over a foraminous floor 21, which in the present instance is shown as formed of reticulated material.

A dead air space 22 will occur beneath the floor 21 and a solid flooring 23, which unites with the wall 11 to provide a complete enclosure and inner wall for the compartment. Spaced some distance beneath the main floor 23 is a false floor 24, which fastens at its opposite ends to the outer walls 12 and forms a horizontal passageway 25 with which the vertical air passage 13 communicates. The outer walls 12 of the structure are continued downwardly below the false floor 24 and form a hollow base 26 upon which the entire structure is superimposed.

This base is formed with a central circular opening 27, which is lined with a tubular heat resisting lining 28 and within which an oil burner 29 is disposed. A bottom wall 30 extends across the mouth of the lining 28 and beneath the burner 29. This burner is fitted with a concaved bowl 31 which will act to throw the heat upwardly and through the opened end of the lining 28, into the compartment 25 with which this tubular lining communicates. Secured upon the underface of the floor 23 is a baffle plate 32 of heat insulating material, which will act to insure that the flame and products of combustion arising from the burner 29 will be deflected and distributed throughout the chamber 25. This heat will pass upwardly

100
105

between the walls 11 and 12 and will be caused to circulate throughout the compartments 13 on the opposite sides of the structure, due to baffle plates 33 and 34, which are arranged between the walls 11 and 12 in staggered relation to each other. These baffles are arranged throughout the side walls of the compartment and over the dome, thus insuring that the heat will 10 be thoroughly distributed as it travels to the outlet pipe 35.

In order to insure a positive circulation of the heated air between the walls 11 and 12 a suction fan 36 is disposed across the outlet pipe 35 and may be operated by a driving pulley 37 and gears 38. It will be understood that the back of the compartment 10 is closed by means of a back wall 39 and that the front is normally 20 closed by two swinging doors 40 and 41, these doors, when open, exposing the complete interior of the heat compartment.

It has been found that it is desirable to circulate fresh air through the compartment 25 containing the material to be dehydrated and thus providing air for carrying off the moisture expelled from the dehydrating material without directly admitting any of the heated air or the products of combustion 30 from the burner. In order that fresh air may be delivered satisfactorily to the drying compartment, it should be uniformly distributed and for that reason a plurality of registers 42 are disposed beneath 35 the foraminous floor 21 and spaced in relation to each other, as more clearly shown in Fig. 1, so that air will be uniformly supplied to the bottom of the heat compartment. This air is conducted to the registers 40 by means of pipes 43, which extend outwardly from the sides and ends of the desiccator and are arranged in substantially lattice shape, thus producing communication 45 between all of the pipes and all of the registers.

Each of these pipes is fitted with a damper 44 and is otherwise provided with a sheet of absorbent material 45 across its mouth for partially saturating the inflowing air with moisture as the members 45 carry this moisture up from liquid containers 46. This insures that when the fruit is of a dry character, the excessive heat will not act to burn the fruit during the 50 drying process but will add sufficient moisture to prevent a thorough desiccation of the material without objectionable results. Fresh air may also be admitted to the heat compartment 10 through openings 55 47 in the ends of the compartments, which openings are completely or partially closed by shutters 48. The moisture-laden air which passes off from the trays of fruit is 60 gathered within conical hoods 49 and conveyed to the outlet pipe 35 through pipes 65

50. These hoods are disposed directly over the tops of the piles of trays and thus will certainly receive the rising vapor and carry it away. The fan 36 will also exert a suction action upon the air within the drying 70 compartment, which will create a draft and insure a desirable circulation of the fresh air through the drying compartment at all times.

In operation, the heat compartment is 75 charged with trays 14 which have been filled with the material to be dried and placed in the compartment; preferably upon the cars 15. The doors are then closed and heat generated by the burner 29. This generation of heat will cause the interior wall 11 of the heat compartment to radiate sufficient heat to the drying compartment to dry the material on the trays, it being understood that these trays may be of any desired construction and may have floors of foraminous material, if desired.

The circulation of the products of combustion through the passageways 13 may be retarded by means of dampers 51, particularly 90 shown in Fig. 2. This will act to hold the heated air down at the sides of the trays and thus intensify the heat, if desired. Simultaneous with the development and the circulation of the heated air, fresh air will be 95 drawn in through the numerous pipes 43 and will pass upwardly through the floor registers 42 to circulate through the heat compartment and carry off the moisture expelled from the drying material. This 100 moisture will then pass into the hoods 49 and be carried outwardly through the pipe 35.

It will thus be seen that the drying apparatus here disclosed insures that the material being dried will not be contaminated by the products of combustion, although being furnished with sufficient heat for drying purposes, and that effective means are provided for carrying away the water from 105 the material as it is expelled, thus preventing a stewing action which is now produced by many structures of this class. It will further be noted that the temperature may be easily regulated and that the fresh air 110 may be laden with moisture as it enters the heat compartment in the event that there is a possibility of burning the material.

While I have shown the preferred form of my invention, various changes in the construction and arrangement of the several parts herein shown and described may be resorted to without departing from the spirit of my invention, as disclosed in the appended claims.

Having thus described my invention, what I claim and desire to secure by Letters Patent is—

1. A desiccator having a drying compartment within which material to be dehy- 130

- drated may be placed, means for producing a circulation of heated air around said compartment without passing therethrough, means for conveying fresh air into the drying compartment and distributing it uniformly thereover, and means for completing the circulation of said fresh air through the drying compartment, said means including a false foraminous floor, a plurality of intersecting fresh air pipes beneath said floor with controlling registers, conical discharge domes above the drying compartments, conducting pipes therefrom, and a connected suction fan.
2. A desiccator having a drying compartment within which material to be dehydrated may be placed, means for producing a circulation of heated air around said compartment without passing therethrough, means for conveying fresh air into the drying compartment and distributing it uniformly thereover, means for completing the circulation of said fresh air through the drying compartment, and means for positively creating a draft through the drying compartment and in the heat compartment therearound.
3. A desiccator having a central drying compartment enclosed by a heat radiating wall, an outer jacket enclosing said wall and spaced therefrom, heat generating means below said drying compartment and communicating with the space between the two walls thereof, a foraminous floor spaced a distance from the heat radiating floor of the drying compartment, means for uniformly distributing fresh air beneath said floor to circulate through the drying compartment and trays disposed therein, hood members within the drying compartment and over said trays, pipes and a suction fan through which the circulation of said fresh air is completed, and means for insuring and regulating uniform circulation of the heated air between the walls of the drying compartment, including staggered baffle plates within said compartment.
4. A desiccator having a central drying compartment enclosed by a heat radiating wall, an outer jacket enclosing said wall and spaced therefrom, heat generating means below said drying compartment and communicating with the space between the two walls thereof, a foraminous floor spaced a distance from the heat radiating floor of the drying compartment, means for uniformly distributing fresh air beneath said floor to circulate through the drying compartment and trays disposed therein, hood members within the drying compartment and over said trays, through which the circulation of said fresh air is completed, means for insuring and regulating uniform circulation of the heated air between the walls of the drying compartment, and means for supplying the heated air between the walls of the drying compartment, and means for supplying the inflowing fresh air with moisture.
5. A desiccator having a drying compartment, the front and back walls of which are solid and the side walls of which are false to provide a heat circulating space from which heat may be radiated to the drying compartment, baffle members arranged in staggered relation to each other within said space to insure uniform circulation, dampers for regulating said circulation, means for heating the air circulating through said compartment, and means for producing a positive suction draft for said heated air.
6. A foraminous false floor within the drying compartment, a plurality of intersecting fresh air pipes passing beneath said false floor and formed with outlet registers at their intersections for uniformly supplying fresh air to the drying compartment, and conical hoods within the drying compartment and through which the circulation of said air may be completed.
7. In a desiccating apparatus of the character described, drying compartments, a plurality of fresh air pipes, a foraminous floor above said pipes, convergent hoods above the drying compartments with discharge pipes and a suction fan, double walls surrounding said drying compartment, forming heat conducting passages with staggered baffle plates and retarding dampers.
8. A desiccating apparatus comprising a drying compartment, means for heating the same, means for creating a uniform distribution of fresh air within the drying compartment, a hood member within the drying compartment, and disposed above articles to be dried, and a flue leading from the dome, and creating a draft to carry away the moisture-laden air from the articles drying within the compartment.
9. A desiccating apparatus comprising a drying compartment, means for heating the same, means for uniformly distributing fresh air to said compartment, a flue accommodating the draft of fresh air passing through the drying compartment and the heated air, indirectly heating the same, means for creating a forced draft for said flue, and bell-shaped hoods within the drying compartment and with their opened mouths over the articles being dried, said hoods communicating with the flue and carrying away the moist air from the drying compartment.
- In testimony whereof I have hereunto set my hand in the presence of two subscribing witnesses.

EDWARD D. ARIAN.
